UNITED STATES PATENT OFFICE.

FRANCESCO CIRELLI, OF PHILADELPHIA, PENNSYLVANIA.

TALKING-MACHINE.

1,357,382.

Specification of Letters Patent.

Patented Nov. 2, 1920.

Application filed August 5, 1919. Serial No. 315,403.

To all whom it may concern:

Be it known that I, FRANCESCO CIRELLI, a subject of the King of Italy, residing at Philadelphia, in the county of Philadelphia and State of Pennsylvania, have invented certain new and useful Improvements in Talking-Machines, of which the following is a specification.

One object of my present invention is to 10 provide a talking machine which will be so constructed that it will play records of the "Victor" and "Edison" type without altering, changing or in any manner affecting the structure of the sound box, tone arm or connected parts.

Another object of my invention is to so 20 mount a sound box, such as the sound box which forms a part of my co-pending allowed application for United States patent, Serial No. 248,557, that the mere swinging of the sound box from one side of the center of a disk record to the other side of said center will place the sound box in operative position to play records of the above 25 mentioned types.

A further object of my present invention is to connect the sound box to a horn which is pivotally supported between its ends.

A further object of my invention is to 30 connect the sound box to a second horn which, in turn, is supported by said first horn; said second horn serving to overbalance and hold the sound box in a raised position after having been raised.

Another object is to make my invention 35 of a simple construction and so that it can be quickly and easily connected to any supporting structure adjacent a record support and requires no special form of cabinet to 40 apply the above mentioned parts thereto.

These objects, and other advantageous ends which will be described hereinafter, I attain in the following manner, reference being had to the accompanying drawings in 45 which—

Figure 1 is a top plan view showing my invention in a position which it occupies in playing a record of the "Victor" type,

Fig. 2 is a side elevation of Fig. 1 looking 50 in the direction of the arrow α ,

Fig. 3 is a view of similar nature to Fig. 1 showing my invention having been swung into a position for playing a record of the "Edison" type; it merely being necessary 55 to change the position of the reproducing

needle from one duct of the needle holder to another duct of the needle holder as will hereinafter be more clearly described,

Fig. 4 is a side elevation looking in the direction of the arrow γ of Fig. 3,

Fig. 5 is an enlarged fragmentary elevation showing my needle holder,

Fig. 6 is a transverse section taken on the line 6—6 of Fig. 5 and drawn on a smaller scale,

Fig. 7 is a section taken on the line 7—7 of Fig. 6,

Fig. 8 is a section taken on the line 8—8 of Fig. 6,

Fig. 9 is a fragmentary section taken on 70 the line 9—9 of Fig. 1, and

Fig. 10 is a section taken on the line 10—10 of Fig. 9.

Referring to the drawings, 11 represents a box or cabinet which may be of any usual construction including a turntable 12 which can be operated by any suitable means (not illustrated). This turntable is adapted to support a record, such for example as the record 13 in Figs. 1 and 2 and the record 14 in Figs. 3 and 4. As illustrated the cabinet 11 includes a lid 15 which is hinged to the body portion 16 of the cabinet as shown at 17. A post 18 is screwed into the lid 15, said post having a flange 19 thereon. The 85 portion of the post above the flange 19 extends through a horn 20 which is located between the opposite ends 21 and 22 of said horn, as clearly shown in Figs. 1 to 4 inclusive. A sleeve or bushing 23, which is preferably made of non-metallic material, such for example as rubber, surrounds the post 18 and extends through the horn 20. Thus the horn 20 is free to rotate on the post 18 and rests on the flange 19, thereby supporting 90 the horn at the proper elevation. 95

The horn 20 has a transversely extending T-branch 24 at the end 22, said T-branch forming a bearing for a tube 25, said tube extending entirely through the branch 24 100 and having an opening 26 (see Figs. 9 and 10) which is adapted to register with the sound outlet passage 27 in the horn 20. The tube 25 is V-shape in longitudinal section, as clearly shown in Figs. 1 and 3, 105 and the end 28 supports a sound box 29 in a position at right angles to the axis of said end portion. The post 18 is so positioned with respect to the center 30 of the turntable 12 and the end 28 and the sound box 29 110

is so positioned with respect to the center 30 and post 18 that when in the position shown in Fig. 1, the sound box is substantially tangent to the grooves 31 of the record 13 and when swung on the post 18 as a pivot into the position illustrated in Fig. 3, the sound box will occupy a position transverse to the grooves 32 of the record 14 or, in other words, the plane including the diameter of the sound box transversely intersects the grooves 32 of the record 14. The needle holder 33 has two needle ducts 34 and 35 which extend downwardly at angles in planes substantially at right angles to each other as clearly shown in Figs. 5 to 8 inclusive. In order to play the "Victor" type of record, such for example as shown in Figs. 1 and 2, an ordinary reproducing needle 36 is placed within the duct 35 and secured therein by a set screw 37. The needle 36 extends at the proper incline in accordance with the direction of rotation of the record as shown by the arrow *a*. When it is desired to play a record of the "Edison" type, the sound box is swung into a position shown in Fig. 3 at the opposite side of the center 30 and the reproducing needle 36 is secured within the duct 34 by the set screw 37; this position being clearly illustrated in Figs. 3 and 4.

A second horn 38 is adjustably secured to the opposite end 39 of the tube 25, said horn 38 having a branch sleeve 40 which frictionally fits the end 39 of the tube 25; the friction between the branch 40 and the end 39 of the tube 25 being sufficient to cause the horn 38 to swing when the sound box 29 is raised; it being noted that the tube 25 freely rotates in the branch 24 of the horn 20. The weight of the horn 38 is such, when the latter is swung over the top of the tube 25, that the overhanging portion of the horn 38 will be sufficient to hold the sound box in a raised position and the flared end 41 of the horn 38 will rest against the top of the horn 20 and the entire structure can be freely swung around the post 18 as a pivot.

By having the horn 20 pivoted between its ends the portion between the end 21 and the pivot post 18 will serve as a counter-balance to relieve the post 18 of any bending action. Furthermore, I preferably make the horn 28 of such length that when it is swung into a position holding the sound box out of engagement with the record that the flat end 41 will engage and rest upon the horn 20 at a position between the pivot post and the end 21, thereby also serving to throw an additional portion of the weight between the post 18 and the end 21.

In actual practice and demonstration, I have found that by arranging the parts as above described in view of the difference in the characteristics of the grooves in the

"Victor" and "Edison" type of record as above mentioned that practically similar results are obtained in the two types of records and that the arcuate path of travel of the reproducing needle toward the center is such as to properly engage the grooves of both types of record without cutting or injuring the same. In the one type of record, the vibrations are caused laterally and these vibrations, such for example as in the form shown in Figs. 1 and 2, are transferred transversely to the plane including the width of the diaphragm in the sound box. In the form shown in Figs. 3 and 4, the vibrations are effected in a direction transversely to the direction of vibration of the form shown in Figs. 1 and 2 and in view of the position of the diaphragm in Figs. 3 and 4, these vibrations will also be transferred transversely to the width of the diaphragm, thereby giving practically similar results.

It will thus be noted that with my invention it is unnecessary to change or alter the sound box or the tone arm or any connecting parts when it is desired to change from one type of record to that of the other. It is merely necessary to insert the needle in one or the other of the two ducts and swing the sound box so that the needle engages the initial groove at one side or the other of the center of rotation of the record according to the type of record to be played.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. The combination in a talking machine of a rotatable record support; a sound box; and means supporting said sound box and movable in a path from a position in which the width of said sound box is in a plane substantially tangent to the curvature of the playing grooves, on one side of the center of rotation of a record, into a position in which the width of the sound box is in a plane substantially transverse to the curvature of said grooves at the opposite side of the center of rotation of said record; substantially as described.

2. The combination in a talking machine of a rotatable record support; a sound box; and pivoted means for supporting said sound box, said sound box being operatively supported on said means at a slant to the pivotal length of said means, said means being movable on said pivot in a path to present said sound box substantially

- tangent to the playing grooves on one side of the center of rotation of the record into a position substantially transverse to said grooves at the opposite side of the center of 5 rotation of said record; substantially as described.
3. The combination in a talking machine of a rotatable record support; a sound box; and means supporting said sound box and 10 movable in a path from a position in which the width of said sound box is in a plane substantially tangent to the curvature of the playing grooves, on one side of the center of rotation of a record, into a position 15 in which the width of the sound box is in a plane substantially transverse to the curvature of said grooves at the opposite side of the center of rotation of said record, said means including a horn and a tube 20 connected to said horn and having an end portion extending at a slant to the length of said horn and to which said sound box is attached, said sound box having its width included in a plane extending substantially 25 at right angles to the axis of said inclined portion of the tube; substantially as described.
4. The combination in a talking machine of a rotatable record support; a sound box; and means supporting said sound box and 30 movable in a path from a position in which the width of said sound box is in a plane substantially tangent to the curvature of the playing grooves, on one side of the center of 35 rotation of a record, into a position in which the width of the sound box is in a plane substantially transverse to the curvature of said grooves at the opposite side of the center of rotation of said record, said means
- including a horn and a tube pivotally connected to said horn and having an end portion extending at a slant to the length of said horn and to which said sound box is attached, said sound box having its width included in a plane extending substantially 40 at right angles to the axis of said inclined portion of the tube; and a second horn connected to said tube; substantially as described. 45
5. The combination in a talking machine 50 of a rotatable record support; a sound box; means supporting said sound box, said means including a horn; a tube connected to said horn and having an end portion extending at an angle to the length of said horn and to which said sound box is attached, said sound box having its width included in a plane extending substantially 55 at right angles to the axis of said inclined portion of the tube; and a pivot support for said 60 horn between its ends; substantially as described.
6. The combination in a talking machine of a rotatable record support; a sound box; and means supporting said sound box, 65 said means including a horn and a tube connected to said horn and having an end portion extending at a slant to the length of said horn and to which said sound box is attached; substantially as described. 70

In testimony whereof I have signed my name to this specification in the presence of two subscribing witnesses.
